HOT WATER HEATER

Henry S. Dodd, Toronto, Ontario, Canada, assignor to Canadian Chromalox Company Limited, Toronto, Ontario, Canada

Application May 25, 1933, Serial No. 672,829

7 Claims. (Cl. 219—38)

This invention relates to heaters of the electric type, in which a boiler has one or more vertically arranged tubes extending therethrough, in which tubes are positioned heating elements packed in sand or other powdery material. The leads for the element are usually connected at the top. In use the element expands and contracts, as it is heated up and cools. The result is that as the element contracts or shortens, the sand or other packing material slides in below the element, consequently when the element is again heated, the expansion must all take place in the upward direction on account of the difficulty in working down into the packing which has slid down below the element. This sequence is followed over and over, and each time the element cools and contracts, more and more packing slides down below it with the result in time the element reaches the top of the tube, and either forces off the cap or causes a bending and breaking down of the element.

My object therefore, is to devise a construction which will prevent this upward creeping of the element, and I attain my object by means of the constructions hereinafter described and illustrated in the accompanying drawing in which

Fig. 1 is a vertical section of a water heater constructed in accordance with my invention;

Fig. 2 a cross section through the same; and Fig. 3 a detail on an enlarged scale of the element anchoring means.

In the drawing like numerals of reference indicate corresponding parts in the different figures.

1 is a cylindrical casing having an inwardly directed flange 2 at its upper end and an inwardly directed flange 3 at its bottom, the lower flange being of greater width than the upper flange.

To the upper flange 2 is secured outside the tank the upper closure member 4 by means of studs or bolts 5. To the lower flange 3, by studs or bolts 6, is secured within the tank the closure member 7, which closure member is of a size to permit its withdrawal through the top of the tank when the closure member 4 is removed. Suitable packing will be interposed between the closure members and flanges to make the joints watertight.

The closure members 4 and 7 are provided with a plurality of aligned holes and in these holes are positioned tubes 8. Three are shown in the drawing although any desired number may be employed. The closure members 4 and 7 and the tubes 8 are secured together to form a unitary construction, which, after removing the studs 5

and 6, may be removed through the upper end of the tank.

Within the tubes 8 are located the heating elements. The heating elements employed may be of various types, but I preferably employ a sheathed element 9 in which the resistance is imbedded in a powdered refractory material compacted under pressure. As the elements 9 do not fill the tubes 8, and to prevent the elements from damage through warping, the tubes 8 about the elements are filled with powdered material 10, preferably what is commercially known as silver sand. The lower ends of the tubes are provided with caps 11, which in the drawing are shown as reducing couplings, the bottoms being closed by plugs 12.

As stated in the preamble of the specification, it is desired to prevent the upward creeping of the elements 9 due to expansion and contraction, and I therefore provide means for anchoring the elements 9.

The anchoring means comprises a hook member 16, the hook of which extends through a hole in the end of the element casing and has a nut 17 set up thereon. The stem of the hook member extends through a hole in the plug 12, and has a nut 18 above the plug and a nut 19 below the plug to lock the hook member in position. The element casing stops short of the upper end of the tube so that it is free to expand upwardly in the powdered filling.

In the event of a breakdown in an individual element, the nut 19 is first removed, then the plug 12, which allows the powdered material to escape, and the element may then be removed through the upper end of the tube. The plug 12 will then be replaced, a new element placed in position and anchored by screwing on the nut 19, and the tube again filled with powdered material.

The heater may be provided with sleeves 13 encasing the tubes 8 for the purpose of causing a circulation within the tank. To facilitate removal, the sleeves may be formed in two halves secured together by screws 14 or the like and will be supported on brackets 15 mounted on the sides of the tubes 8. With this arrangement, when the elements are in use, the water as heated, tends to travel upwardly between the tubes and sleeves, the cold water moving downwardly outside the sleeves.

What I claim as my invention is:

1. In an electric heater, the combination of a vertically arranged tubular member; a sheathed heating element within the tubular member; a closure for the lower end of said tubular member;

and pulverized material surrounding said element within the tubular member, said heating element having the lower end of its sheath anchored to prevent upward movement, and its upper end free to expand upwardly.

5. In an electric heater, the combination of a vertically arranged tubular member; a sheathed heating element within the tubular member; a closure for the lower end of said tubular member; and pulverized material surrounding said element within the tubular member, said heating element having the lower end of its sheath anchored to said closure to prevent upward movement, and its upper end free to expand upwardly.

10. 6. In an electric heater, the combination of a vertically arranged tubular member; a sheathed heating element within the tubular member; a removable closure for the lower end of said tubular member; and pulverized material surrounding said element within the tubular member, said heating element having the lower end of its sheath anchored to prevent upward movement, and its upper end free to expand upwardly.

15. 7. In an electric heater, the combination of a vertically arranged tubular member; a sheathed heating element within the tubular member; a removable closure for the lower end of said tubular member; and pulverized material surrounding said element within the tubular member, said heating element having the lower end of its sheath anchored to said closure to prevent upward movement, and its upper end free to expand upwardly.

20. 8. In an electric heater, the combination of a vertically arranged tubular member; a sheathed heating element within the tubular member; a closure for the lower end of said tubular member; and pulverized material surrounding said element within the tubular member, said heating element having the lower end of its sheath anchored to prevent upward movement, and its upper end free to expand upwardly.

25. 9. In an electric heater, the combination of a vertically arranged tubular member; a sheathed heating element within the tubular member; a closure for the lower end of said tubular member; and pulverized material surrounding said element within the tubular member, said heating element having the lower end of its sheath anchored to prevent upward movement, and its upper end free to expand upwardly.

30. 10. In an electric heater, the combination of a vertically arranged tubular member; a sheathed heating element within the tubular member; a closure for the lower end of said tubular member; and pulverized material surrounding said element within the tubular member, said heating element having the lower end of its sheath anchored to prevent upward movement, and its upper end free to expand upwardly.

35. 11. In an electric heater, the combination of a vertically arranged tubular member; a sheathed heating element within the tubular member; a closure for the lower end of said tubular member; and pulverized material surrounding said element within the tubular member, said heating element having the lower end of its sheath anchored to prevent upward movement, and its upper end free to expand upwardly.

heating element within the tubular member; a closure for the lower end of said tubular member, said closure having a hole formed therethrough; pulverized material surrounding said element within the tubular member; a hook member having its hooked end engaging the lower end of the sheath said element and its stem extending through said closure; and a nut on said stem below the closure, and its upper end free to expand upwardly.

10. 12. In an electric heater, the combination of a vertically arranged tubular member; a sheathed heating element within the tubular member; a closure for the lower end of said tubular member, said closure having a hole formed therethrough; pulverized material surrounding said element within the tubular member; a hook member having its hooked end engaging the lower end of the sheath said element and its stem extending through said closure; a nut on said stem below the closure; and a nut on said stem above the closure, and its upper end free to expand upwardly.

15. 13. In an electric water heater, the combination of a casing; a tubular member within the casing and having its ends extending through the top and bottom thereof; a sheathed heating element within the tubular member; a closure for the lower end of said tubular member; and pulverized material surrounding said element within the tubular member, said heating element having the lower end of its sheath anchored to prevent upward movement, and its upper end free to expand upwardly.
